ELECTRIC CONNECTER

Hugo H. Wermine, Villa Park, Ill., assignor to
 Belden Manufacturing Company, Chicago, Ill.,
 a corporation of Illinois

Application September 4, 1929, Serial No. 390,322

9 Claims. (Cl. 173—361)

This invention relates to electric connectors such as separable electric connectors and the principal objects of the invention are to provide a strong and durable connector structure which will be practically unbreakable and which will be particularly adapted for heavy duty service as, for instance, in shops and other industrial applications.

Other objects and advantages of the invention will be understood by reference to the following specification and accompanying two sheets of drawings in which I have illustrated a connector embodying a selected form of my invention, certain modifications or adaptations being also shown.

In the drawings:

Fig. 1 is a longitudinal sectional view through the axis of a connector, the section being taken in a plane extending through the contact prongs.

Fig. 2 is also a sectional view taken through the axis of the connector but on a plane at right angles to the plane of the section of Fig. 1, and certain parts being shown in elevation to facilitate illustration.

Figs. 3 and 4 are sections on the lines 3—3 and 4—4 respectively of Fig. 1.

Figs. 5, 6 and 7 illustrate the connector of Figs. 1 to 4 inclusive as modified to form a three contact connector such as is required for three wire circuits, Fig. 5 being an end elevation, Fig. 6 an axial section similar to Fig. 2, and Fig. 7 a section on the line 7—7 of Fig. 6.

Figs. 8 and 9 are sectional illustrations similar to Figs. 1 and 2 of a female connector structure embodying the principles of my invention, and Fig. 10 is a section on the line 10—10 of Fig. 9.

Referring now to the drawings, a male connector plug embodying the features of my invention is shown in Figs. 1 to 4 inclusive and includes a main body part 12 which includes a rear or shank part 13 and a front, casing or housing part 14. The shank part 13 is tubular as shown, and provided with an opening 15 at its end which is adapted to snugly fit a conductor cord 16. In the present instance, I contemplate using a rubber or like covered cord 16 which is substantially circular in cross-section and will snugly fit the opening 15.

The front part of the main body member 12 is in the nature of a recessed or hollowed out enlargement of the shank which forms an outwardly facing shoulder 17 at the bottom of the recess, i. e. where the enlarged recess in the housing portion meets the bore of the shank. The shoulder portion of the main body part 12 is provided

with sockets such as 18 for receiving the inner ends 19 of contact prongs 20—20. The inner ends of the contact prongs are thus positioned with respect to the main body part and also with respect to each other.

The contact prongs 20 are provided with longitudinally spaced ears 21 and 22 which extend laterally inwardly from the respective prongs as clearly shown in Fig. 4. Binding posts or screws 23 engage threaded apertures in the respective contact prongs, preferably between the ears 21 of each of the prongs, these binding posts serving to facilitate connection of electric conductors such as 24 to the respective prongs.

Because of the desirable width of the conductor receiving bore in the shank, the inner end portions of the contact prongs are spaced apart somewhat more than the standard spacing of contact prongs. In order that the outer end portions of the prongs be spaced the said standard distance apart, the contact prongs are offset inwardly or towards each other as indicated at 25 so that the outer end portions 26 thereof are brought into the desired position relative to each other.

For further supporting the contact prongs, I provide an auxiliary body member 27 which is in the form of a plug adapted to fit in the bore or recess of the casing part 14 of the main body member, the said plug part being provided with suitable recesses for receiving parts of the contact prongs and with openings for permitting the contact prongs to project outwardly from the outer end of the plug. As shown in Figs. 1 to 4 inclusive, the plug 27 is in the form of a cylindrical lower or inner part 28 and an enlarged outer or top part 29 which is further provided with an annular rib 30. The rib 30 fits into a groove 31 provided in the outer end of the main body part so that the two body parts are interlocked, one with the other and thus maintained against separation. One of the body parts is made of resilient material such as rubber so as to be capable of being distorted to permit assembling of said parts, or both parts may be made of such resilient material. In the present instance, I have shown both body parts as being made of resilient material, such as rubber, which is also an electrical insulation material.

The inner portion 28 of the plug is provided with recesses, such as 32, of sufficient depth and width to receive the contact prong ears 21 and 22 (see Fig. 4). The length of the recess 32 is also preferably such that the ears 21 and 22 will fit within the length of the said recesses.

Above the comparatively wide recess 32, the plug part 29 is provided with narrower recesses 34, approximately the same width as the width of the contact prongs. The recesses 34 terminate short of the outer end of the plug part so as to leave a comparatively thin end wall portion 35, the latter being provided with openings 36 through which the prongs 20-20 extend outwardly beyond the end of the plug. The reduced width 5 recess 34 communicates with the wide recess 32, incidently forming inwardly or downwardly facing shoulders such as 37 which are adapted to be engaged by the upper edges of the ears 21 of the contact prong, to thereby limit outward 10 endwise displacement of the said contact prong. The lower or inner contact prong ears 22 are seated on the shoulder 17 so as to prevent inward endwise displacement of the prongs and also to prevent the extreme inner ends of the contact prongs from gradually and continually cutting 15 further and further into the shank.

The spaced arrangement of the ears 21 and 22 serves to provide convenient means for securing the conductor and contact prongs together. As 20 shown in Figs. 1 and 2, the conductors separate upon leaving the main portion of the conductor, each extending upwardly and through the respective plug recesses inside of the respective contact prongs. The conductor is brought outwardly between the said ears and across the front of the contact prong, and then turned inwardly and upwardly where it is secured to the contact prong through the agency of the binding posts 23-23. This arrangement of conductors 25 serves to prevent breaking of the connection between the respective conductors and contact prongs when the cord is subjected to excessive strains. The housing part 14 of the outer body member is also preferably provided with longitudinally extending grooves 38 which are adapted to receive the projecting ends of the binding posts 23-23 whereby relative rotation between the outer and inner body parts is effectively prevented.

In the triple prong connector structure shown 45 in Figs. 5 to 7 inclusive, the inner or plug body portion 27^a is provided with three recesses 32^a which receive contact prongs in substantially the same manner as the contact prongs are received 50 in the plug part 27 of Figs. 1 to 4 inclusive. However, in a triple prong connector, two of the prongs 26^a and 26^b are arranged with their widths 55 extending transversely of radii or parallel with tangents of the plug, and the third contact prong 26^c is arranged with its width extending radially of the plug. The contact prong 26^c is twisted intermediate its length and preferably above the upper ears as indicated at 39 so that the lower or inner portion of the contact prong has the 60 same relation to the plug body as the inner portions of the other contact prongs. As shown in Fig. 7, the ears 21^a which correspond to the ears 21 in the structure shown in Figs. 1 to 4, may be bent inwardly to fit snugly in the recesses 32^a 65 and they may be made of such length that they will serve to position the prongs transversely by engaging the bottom of the respective recesses.

In Figs. 8 to 10 inclusive, I have shown a female connector structure which includes an outer body part 40 similar in general characteristics to the outer body part 12 of the male connector structure of Figs. 1 to 4 inclusive, and an inner or plug body part 41 which is similar in general characteristics to the plug part 27 of the 70 said Figs. 1 to 4. However, in the female plug

structure, contacts of a different type are provided. In this instance, the contacts are in the form of clips which are formed of like but oppositely facing resilient members 42 and 43, the lower end portions of which are preferably flat 5 and disposed face to face, and the upper end portions of which are suitably shaped to form spring clips which will grip the prongs of a male connector to form good electrical connection therewith. The flat lower end portions of the 10 clip members 42 and 43 are permanently held in assembled relation by being disposed against a rigid metal piece 44 which is provided with ears 45 which are bent inwardly across the thicknesses of the clip members and then transversely 15 across the inside face thereof as best shown in Fig. 8. Binding post screws such as 46, threadedly engaging the rigid metal plate pieces 44 also serve to hold the clip members in assembled relation as will be readily understood from inspection of Figs. 8 and 10.

The plug body 41 is provided with recesses 47 for receiving the respective clips, and the outer end of the plug is provided with openings such as 48 through which the prongs of a male connector 25 are adapted to be inserted into the recesses 47 and between the clip members. The conductors 49-49 of a duplex conductor cord are respectively connected to the clips in the recesses 47-47, the conductors being separated initially by means of 30 a spreader part 50 formed integral with the plug body and then passed upwardly into recesses such as 51 at opposite sides of the plug, from which recesses the conductors communicate with the recesses 47-47 through apertures 52-52 as clearly shown in Fig. 10.

For preventing disassembling of the plug part 41 and body part 40, the said parts are provided with interlocking connection which may conveniently consist of an annular flange or rib-like 40 part 53 on the plug 41, and an inwardly projecting annular flange or rib-like part 54 in the mouth of the main body 40. One or both of the body parts may be made of resilient insulating material such as rubber whereby the parts are 45 distortable to permit the same to be assembled. In the present instance, I contemplate making both parts of resilient material although this is obviously not necessary. When the body parts are thus interlocked, the contact elements are anchored against outward displacement by being seated at their inner ends on the shoulder 57 in the main body part 40 and against outward endwise displacement, partly by engagement at their outer ends with the inside face of the plug wall 55 adjacent the openings 48. For further preventing endwise displacement of the contact elements, I provide the rigid metal pieces 44 with outwardly projecting lips 55 which project under an inwardly projecting annular rib 56 provided in the 60 outer body part 40. In assembling the structure, the conductors are threaded through the respective recesses and openings and then connected to the respective contact elements, after which the latter are positioned in the recesses of the plug. 65 The plug, with the clip members in its recesses, is then pressed inwardly into the housing part of the main body, the annular ribs or flanges 54 and 56 yielding sufficiently to permit the rib 53 of the plug and outwardly projecting lips 55 to pass the 70 same.

From the above description, it will be seen that I have provided a plug structure in which the parts are firmly supported, and in which there is practically no danger of breakage due to any 75

rough handling as connectors of the type herein contemplated are ordinarily subjected. I am aware that changes may be made in the above described structure without departing from the spirit of my invention, the scope of which should be determined by reference to the following claims, construing the same as broadly as possible consistent with the state of the art.

I claim as my invention:

1. In an electric connector, the combination of inner and outer body parts, the outer part having a recess for receiving the inner part, said parts having interlocking engagement maintaining the same in assembled relation, and one of said body parts being made of resilient material so as to be distortable to permit assembling of said parts in said interlocked relation, said inner body part having a longitudinally extending recess in its inner end portion and an opening in its outer end portion communicating with said recess, and a contact member disposed in said recess and provided with means engaging said inner body part at the outer end of said recess and said outer body part at the bottom of the recess therein, thereby to prevent endwise displacement of the contact.
2. In an electric connector, the combination of inner and outer body parts, the outer part having a recess for receiving the inner part, said parts having interlocking engagement for maintaining the same in assembled relation, one of said body parts being made of resilient material so as to be distortable to permit assembling of said parts in said interlocked relation, said inner body part having a longitudinally extending recess in its inner end portion and a opening in its outer end portion communicating with said recess, a contact member fitting in the recess in said inner body part and communicating with the outside of the connector through said opening, said contact member having a pair of longitudinally spaced ears extending laterally therefrom, one engaging said inner body part and the other engaging said outer body part to prevent endwise movement of said contacts relative to said body parts.
3. In an electric connector, the combination of an outer body member having a recess in one end, an inner body part constituting a plug fitting in the recess of said outer body part, said parts having an interlocking connection and one of said parts being made of resilient material and capable of being distorted to permit assembling of said parts in said interlocking engagement, said plug part being provided with a longitudinally extending recess in its inner end portion and an opening in its outer end portion through which said recess communicates with the outside of the plug, a portion of said recess being of greater width than the adjacent upper portion so as to provide a downwardly facing shoulder intermediate the ends of the plug, a contact member disposed in said recess and having an ear extending laterally therefrom and underlying said shoulder, whereby outward displacement of said contact member is prevented, and means for preventing inward displacement of said contact members.
4. In an electric connector, the combination of an outer body part of resilient insulating material, said part having a recess in one end, an inner body or plug part fitting in the recess of said outer body part and having interlocking engagement therewith, said plug part being provided with a pair of relatively spaced and diametrically oppositely disposed, longitudinally ex-

tending recesses in its inner end portion and a pair of openings in its outer end portion spaced inwardly from the periphery of the plug part and communicating respectively with said recesses, a pair of contact prongs fitting respectively in said recesses and extending outwardly through said openings, said plug part being of materially greater length than the spacing of said outwardly extending prong portions and said contact prongs having inner end portions projecting beyond the inner end of said plug, and said body part being provided with recesses for receiving said projecting contact prong inner end portions, said contact prongs being supported by said plug and body parts respectively at points spaced materially longitudinally of the contact prongs, whereby lateral movement of the prongs toward and from each other is effectively resisted.

5. In an electric connector, the combination of a main body member having a conductor receiving opening and a portion having a socket therein spaced laterally from said opening, a contact prong seated in said socket and projecting therefrom, an auxiliary body member interlocked with said main body member and provided with a portion spaced longitudinally from said socket containing main body portion and provided with an opening through which said contact prong projects outwardly, said prong being thereby supported at longitudinally spaced points, one of said body parts being of resilient material and being capable of being distorted to permit interlocking of said parts, and means within said interlocked body parts for preventing outward endwise displacement of said contact prong, said means comprising longitudinally spaced, laterally extending ears carried by said prong, said auxiliary body part being provided with an inwardly facing shoulder engaging one of said ears and said main body part having an outwardly facing portion engaging the other ear.

6. In an electric connector, the combination of a main body part including a rear or shank part and a front or housing part, said shank part being apertured to receive a conductor cord and said housing part having an internal diameter greater than the diameter of said cord receiving opening, whereby an outwardly facing shoulder is formed in said main body part, a socket in said shoulder part, a contact prong having its inner end portion fitting in said socket whereby said inner end portion is maintained in predetermined position, an auxiliary body part constituting a plug fitting in said main body housing part, said plug being provided with a longitudinally extending recess extending from the inner end of the plug to a point adjacent the outer end thereof and with an opening in its outer end portion communicating with said recess, said recess and opening serving to receive the prong, and the outer end portion of the prong extending outwardly through said opening, said main and auxiliary body parts being provided with interlocking means and one of said parts being of resilient material so as to be capable of being distorted to permit assembling thereof in said interlocking engagement, and means carried by said contact prong, engaging said main and auxiliary body parts and located in said auxiliary body part recess for preventing endwise displacement of said prongs.

7. In a device of the class described, the combination of a main cup-shaped body part having an aperture at the base thereof for the passage

of a conductor and having a plurality of relatively spaced sockets also in the base thereof spaced laterally from said aperture, a plurality of contact prongs having their respective inner 5 end portions seated in said sockets and thereby supported against lateral movement toward and from each other, and an auxiliary body part removably seated in and interlocked with said main body part adjacent the rim thereof, one 10 of said body parts being formed of resilient material so as to be capable of being distorted to permit assembly of said body parts into said interlocked relation, and said auxiliary body part having a plurality of apertures therein spaced 15 inwardly from its periphery and aligned respectively with said sockets, said prongs extending outwardly through said apertures in spaced, substantially parallel relation to each other and being maintained against relative spreading and 20 contraction by the cooperative effect of said main body support for the inner end prong portions and said auxiliary body support adjacent said outwardly extending portions.

8. In a connector plug of the class described, 25 the combination of an outer body or casing part, an inner body part fitting inside said casing, said body parts being provided with interlocking means and one of said parts being made of resilient material capable of being distorted to 30 permit assembling of said interlocking parts, said inner body part being provided with a pair of relatively spaced openings extending longitudinally through said part, the forward end portions of said openings being spaced from the pe-

riphery of the inner body part and the rearward portions of said openings being transversely enlarged relative to the forward end portions, and contact members disposed in said openings and projecting forwardly from said inner body part and having offset portions located in said enlarged rearward opening portions, said offset portions having engagement with said inner and outer body parts to prevent longitudinal displacement of said contact members. 10

9. In an electric connector, the combination of a main body member having a conductor receiving opening and a socket therein spaced laterally from said opening, a contact prong having an end portion seated in said socket and 15 projecting therefrom, an auxiliary body member interlocked with said main body member and having an opening extending longitudinally therethrough the rearward portion of said opening being transversely enlarged relative to the 20 forward portion so as to provide a rearwardly facing shoulder in said opening, said contact prong being disposed in said opening and extending forwardly through said opening and projecting beyond the front end of the auxiliary 25 body part and having a laterally extending ear engaging said rearwardly facing shoulder to prevent outward endwise displacement of the prong, one of said body parts being of resilient material and being capable of being distorted 30 to permit the assembly of said parts into interlocked relation.

HUGO H. WERMINE.
